(57) **CLAIM**

The ornamental design for a mesh floor lamp, as shown and described.

DESCRIPTION

FIG. 1 is a perspective view of a mesh floor lamp showing my new design;

FIG. 2 is another perspective view of the mesh floor lamp with different sections rotated thereof;

FIG. 3 is another perspective view of the mesh floor lamp with different sections rotated thereof;

FIG. 4 is another perspective view of the mesh floor lamp with different sections rotated thereof;

FIG. 5 is a front elevational view thereof;

FIG. 6 is a rear elevational view thereof;

FIG. 7 is a left view thereof;

FIG. 8 is a right view thereof;

FIG. 9 is a top plan view thereof;

FIG. 10 is a bottom plan view thereof;

FIG. 11 is an enlarged view of portion 11 of FIG. 1 thereof; and,

FIG. 12 is an enlarged view of portion 12 of FIG. 2.

The long dash-short dash broken lines depict enlargement boundaries that form no part of the claim. The evenly broken lines illustrate portions of the article that form no part of the claimed design.
